[57] CLAIM

The ornamental design for a combined bottle and stopper, as shown and described.

DESCRIPTION

FIG. 1 is a front elevational view of a combined bottle and stopper showing my new design;

FIG. 2 is a side elevational view thereof;

FIG. 3 is a view similar to FIG. 1 but with the stopper removed;

FIG. 4 is a perspective view of the stopper;

FIG. 5 is a top plan view with the stopper in place;

FIG. 6 is a bottom plan view;

FIG. 7 is a rear perspective view;

FIG. 8 is a top plan view with the stopper removed;

FIG. 9 is a rear elevational view with the stopper in place;

FIG. 10 is a sectional view taken on the line 10-10 of FIG. 9; and

FIG. 11 is a sectional view taken on the line 11-11 of FIG. 9.
